UNITED STATES PATENT OFFICE.

ERNEST W. SULLIVAN, OF MANTECA, CALIFORNIA.

TRUCK LOADER.

Application filed August 25, 1926. Serial No. 131,373.

- This invention relates to improvements in truck loading devices and particularly to one of a portable power driven type for enabling sacks and other containers of all kinds to be easily lifted from the ground or the floors of warehouses, docks or other places and loaded onto the truck, thereby eliminating the greater part of the manual physical effort otherwise necessary.
- 10 The principal object of my invention is to provide an apparatus for the purpose which may be easily transported, set in place for operation, and manipulated, and by means of which the containers may be expeditiously loaded onto a truck with a minimum of physical effort and requiring the services of only one man to operate the loader, especially in connection with very heavy and bulky containers.
- 15 A further object is to provide a loader for the purpose which may be easily adjusted to enable the same to be used with equal facility in connection with various types of trucks in which the floors or beds are of different heights from the ground.

- A further object of the invention is to produce a simple and inexpensive device and yet one which will be exceedingly effective for the purpose for which it is designed.
- 30 These objects I accomplish by means of such structure and relative arrangement of parts as will fully appear by a perusal of the following specification and claim.

In the drawings similar characters of reference indicate corresponding parts in the several views:

Fig. 1 is side elevation of my improved loader, the supporting wheel on the near side being removed.

Fig. 2 is a top plan view of the device with the power plant removed.

Referring now more particularly to the characters of reference on the drawings, the loader comprises a container consisting of rigid side frames 1 extending the full length between and supported by which is an endless conveying mechanism of suitable standard form. In the present instance this conveyor consists of transversely spaced chains 2 extending between which at longitudinal intervals are bars 3, on the ends of which are mounted rollers 4 which ride on the floor 5 of the conveyor at the sides thereof. These chains as usual pass over sprocket wheels at the ends of the frames 1, the upper sprocket wheels being mounted on a shaft

6 and the lower ones on a shaft 7. The lower shaft is mounted in bearings 8 which are slideable in the frames 1 and are provided with take-up means of common character so that the tension of the chains can be altered at will.

Disposed under the conveyor intermediate its ends are transverse and longitudinally spaced beams 9 and 10. Leaf springs 11 of suitable form extend between and are connected to said beams, said springs intermediate their ends being attached to a transverse axle beam 12 on the ends of which ground bearing wheels 13 are mounted.

The lower beam 9 is connected to the frames 1 by transverse hinges 14. The upper beam 10 has a turnable shaft 15 mounted thereon, on which shaft are fixed longitudinally extending cams 16, on the upper surfaces of which the frames 1 rest. An arm 17 projects radially from one end of the shaft 15 and is connected by a link 18 to a hand operated lever 19 pivoted on the beam 12 between one of the wheels and the adjacent conveyor frame. Rigid bars 20 connect the beams 9 and 10 so as to unite the same to form a rigid frame. The bar on that side on which the lever 19 is mounted is shaped intermediate its ends to form a notched quadrant for engagement with the pawl 21 of the lever, so that the latter may be held at any desired number of different positions. It will therefore be seen that by manipulating this lever the distance from the frame 1 to the beam 10 may be altered at will, for the purpose hereinafter seen.

Projecting upwardly from the frames 1 between the longitudinal plane of the wheels and the lower end of the conveyor are rigid auxiliary frames 22 on which are mounted a power plant of suitable character such as a small gas engine 23. The longitudinal members 22^a of the frame 22, which actually support the engine, are so disposed as to have a downward slant toward the upper end of the conveyor. The engine is so disposed relative to the axis of the wheels 13 that its weight bears down on the conveyor ahead of said axis and causes the conveyor to normally slope so that the end having the shaft 7 thereon rests on the ground at all times regardless of the weight of the sacks on the conveyor; while the opposite end of said conveyor is maintained some distance above ground. This exact distance of course depends on the total overall length

of the conveyor and the relative position of the wheel axis with respect to such length. When the conveyor is thus positioned the frame members 22^a are substantially horizontal, so that the engine, which is preferably one of the horizontal type, is then resting in its normal position.

In operation the upper end of the conveyor overhangs the bed of the truck, indicated at 24, so that the sacks moving up the conveyor from the lower end thereof will be carried to a point above the truck bed and can then easily be handled by men standing on the truck so as to take the sacks from the conveyor and pack them properly on the truck.

By manipulating the lever 19 to raise or lower the upper end of the conveyor, it will be seen that while the lower end remains resting on the ground the height of the upper end is altered. This enables said end (from which the sacks are taken by the workers) to be maintained at a height convenient for such workers, regardless of whether the truck is one whose bed is relatively low and near the ground, or a considerable distance therefrom.

Projecting ahead of the lower end of the conveyor and hinged thereto is an apron 25 which always rests on the ground when the device is in operation and serves as a means for aiding in the placing of the sacks in position to be engaged and raised by the conveyor.

35 Mounted in and projecting through the frames 1 at a suitable point is a transverse shaft 26, on one end of which is loosely mounted a sprocket wheel 27. The opposite end of this shaft is driven from the engine 23 by suitable means such as a belt drive 28. An endless chain 29 extends about the sprocket wheel 27 and also about a sprocket wheel 30 mounted on the upper conveyor shaft 6; an idler sprocket wheel 31 being 45 mounted on the adjacent frame 1 to engage the upper run of the chain 28 adjacent the wheel 30. Mounted in connection with the sprocket wheel 27 is a clutch member 32 adapted to be engaged by a cooperating clutch member 33 fixed on the shaft 26. The member 33 is connected to a shift arm 34 which is pivoted on a fixed bracket 35. From one end of this arm 34 a rod 36 extends to a lever 37 which is pivoted in connection with the conveyor and is provided with a pawl and quadrant mechanism indicated generally at 38 so that the lever and clutch can be positively held in either its engaged or disengaged position.

Sideboards 39 project upwardly from the frames 1 between the longitudinally spaced frame members 22 so as to avoid any possibility of the sacks catching against said frames as they are moved up the conveyor. A drawbar or tongue structure 40 is connected to and extends ahead of the beam 12 a certain distance for attachment to a truck so that the loader may be transported from one place to the other as may be desired. The tongue is connected to the upper cross beam 10 so as to be rigid therewith and normally slopes up to such an extent relative to the conveyor that when said tongue is connected to the truck and is then in a substantially horizontal position, the lower end 75 of the conveyor will be off the ground. At the same time the normal slope of the conveyor is not altered to such an extent as would cause the engine to have an excessive forward tilt. The use of the springs between the wheels and conveyor reduces the shocks and jars incident to the operation of the engine, and also those incident to transportation and aids in enabling the device to have a long life and give continuous 85 service without trouble, or repairs having to be made.

From the foregoing description it will be readily seen that I have produced such a device as substantially fulfills the objects of 90 the invention as set forth herein.

While this specification sets forth in detail the present and preferred construction of the device, still in practice such deviations from such detail may be resorted to as do not 95 form a departure from the spirit of the invention, as defined by the appended claim.

Having thus described my invention what I claim as new and useful and desire to secure by Letters Patent is:

A truck loader comprising a conveyor structure arranged to rest on the ground at one end and to slope upwardly from said end, a longitudinally extending frame under the conveyor intermediate its ends, means supporting the frame from the ground, hinge connections between the conveyor and frame at the lower end of the latter, cam members turnably mounted on the frame at its upper end and on which the conveyor rests, and manually operated lever means mounted on the frame and connected to the cam members for turning the same to raise and lower the conveyor and cause the same to turn about its hinge connection.

In testimony whereof I affix my signature.

ERNEST W. SULLIVAN.
